UNITED STATES PATENT OFFICE.

JOSEPH C. MCCOMBIE, OF MALDEN, MASSACHUSETTS, ASSIGNOR OF TWO-THIRDS TO WILLIAM S. JACOBS AND WILLARD E. ROBINSON, OF MALDEN, MASSACHUSETTS.

FIRE-ESCAPE.

SPECIFICATION forming part of Letters Patent No. 700,543, dated May 20, 1902.

Application filed October 18, 1901. Serial No. 79,070. (No model.)

To all whom it may concern:

Be it known that I, JOSEPH C. MCCOMBIE, of Malden, in the county of Middlesex and State of Massachusetts, have invented certain new and useful Improvements in Fire-Escapes, of which the following is a specification.

This invention relates to a fire-escape comprising a ladder, preferably flexible and adapted to be folded, and a support adapted to be quickly and conveniently engaged with the wall of a building at the inner side of a window-opening and to project through said opening, so that the ladder may be suspended from a point outside the opening. The invention has special reference to a ladder-supporting means, and has for its object to provide an efficient ladder support or holder having provisions for swinging the ladder to one side of the window with which the support is connected, so that the ladder may be adjusted at one side to the lower window or windows from which flame or smoke may be issuing.

The invention consists in the improvements which I will now proceed to describe and claim.

Of the accompanying drawings, forming a part of this specification, Figure 1 represents a vertical section of a portion of the wall of a building, showing an edge view of my improved ladder-support. Fig. 2 represents a front elevation showing the ladder support adjusted or extended to locate the ladder at one side of the window-opening. Fig. 3 represents a top view of the ladder-support.

The same reference characters indicate the same parts in all the figures.

The support for the ladder which I have here shown comprises a bar *h*, preferably composed of a length of metal tubing, arms *h*' *h*', secured to the ends of the bar and made of sufficient length to extend through a window-opening and engage the inner side of the wall, the arms bearing on the sill of a window-opening and supporting the bar *h* in a horizontal position outside the opening and at a suitable distance from the outer side of the wall, as indicated in Fig. 1. The inner ends of the arms *h*' are provided with hooks *h*², which may enter sockets formed for their

reception in the wall below the window-opening. The ladder-supporting arm *d*, above referred to, is hinged at *d*' to the bar *h*, the hinge being vertical and located between the ends of the bar *h*, its arrangement being such that the arm *d* may be swung horizontally and thus extended to one side of the window-opening, as shown in Fig. 2, the ladder engaged by its hooks *c* *c* with the arm being thus located also at one side of the window-opening and out of line with the lower window or windows, so that a person descending the ladder will avoid smoke and flames that may issue from such lower windows. The arm *d* is provided between its hinged and swinging ends with a downwardly-projecting foot *d*², which when the arm is extended, as shown in Fig. 2, bears upon a seat *d*³, formed to support it on the bar *h*, said seat and foot supporting the arm at a point between its hinged and swinging ends, thus preventing it from sagging unduly under the weight of the ladder. The seat *d*³ is shown in Fig. 3 as provided with a locking-spring *d*⁴, having an orifice *d*⁵, adapted to engage the bottom portion of the foot *d*² to lock said foot to the seat *d*³ and prevent the arm *d* from swinging loosely, a slight downward movement of the spring being required in order to disengage it from the foot *d*².

e represents a stud which projects downwardly from the swinging end of the arm *d* and is adapted to be engaged with a socket *f*, formed in the end of the bar *h* opposite the end having the seat *d*³, so that when the arm is not extended, but stands wholly over the bar *h*, the stud *e* and socket *f* will interlock and prevent loose swinging movement of the arm.

To enable a person to pass readily from the window-opening to the ladder when the latter is adjusted at one side of the window-opening, as shown in Fig. 2, I suspend from the bar *h* a short ladder, which may be of the same construction as that above described, said short ladder being composed of a suitable number of sections *a* *a*' and rungs *b*. It will be seen that the short ladder above referred to is directly under the window-opening, so that a person can first step upon it

and then easily step across to the main ladder, supported by the arm *d*. It is obvious that the short ladder may be of any suitable construction and may comprise one or more steps or rungs suitably supported upon the bar *h*.

I claim—

1. In a fire-escape, a ladder-support consisting of a bar having arms adapted to extend through a window-opening in a building-wall and formed to engage the inner side of the wall, the said arms supporting the bar in a horizontal position outside the window-opening, a ladder-engaging arm hinged at one end to said bar at a point between the ends of the latter and adapted to swing horizontally to one side of the window-opening to extend the arm and locate the ladder out of the line of a lower window or series of windows, and supporting members on the arm and bar, arranged to support the arm between its hinged and swinging ends when the arm is extended.
2. In a fire-escape, a ladder-support comprising a bar having arms adapted to extend through a window-opening in a building-wall and formed to engage the inner side of the wall and support the bar horizontally outside the opening and a ladder-engaging arm hinged at one end to the bar at a point between the ends of the latter and adapted to be extended by a horizontal swinging movement to one side of the window said arm having a downwardly-projecting foot between its hinged and swinging ends, while the bar has a seat which supports said foot when the arm is extended, said seat and foot having interlock-

ing members which prevent the loose swinging of the extended arm.

3. In a fire-escape, a ladder-support comprising a bar having arms adapted to extend through a window-opening in a building-wall and formed to engage the inner side of the wall and support the bar horizontally outside the opening, and a ladder-engaging arm hinged at one end to the bar at a point between the ends of the latter and adapted to be extended by a horizontal swinging movement to one side of the window, said arm having a downwardly-projecting stud at its swinging end while the bar has a socket arranged to engage said stud when the arm is not extended.

4. In a fire-escape the combination of a ladder-support comprising a bar having arms adapted to extend through a window-opening in a building-wall and formed to engage the inner side of the wall and support the bar horizontally outside the opening, and a ladder-engaging arm hinged at one end to the bar at a point between the ends of the latter and adapted to be extended by a horizontal swinging movement to one side of the window, a ladder suspended from said arm, and one or more ladder rungs or steps suspended from said bar, said rungs or steps enabling a person to reach the ladder on the extended arm substantially as described.

In testimony whereof I have affixed my signature in presence of two witnesses.

JOSEPH C. McCOMBIE.
